GEORGE B. CUMMINGS, OF CAMBRIDGE, MASSACHUSETTS.

Letters Patent No. 99,167, dated January 25, 1870.

IMPROVEMENT IN SHEET-GAUGES FOR PRINTING-PRESSES.

The Schedule referred to in these Letters Patent and making part of the same.

To all whom it may concern:

Be it known that I, GEORGE B. CUMMINGS, of Cambridge, in the county of Middlesex, and State of Massachusetts, have invented Improvements in Sheet-Gauges or Guides for Printing-PresSES; and I hereby declare that the following is a full and exact description thereof, and reference is made to the accompanying drawings, and to the letters of reference thereon, as parts of the specification.

Figure 1 is a perspective view of the gauge.

Figure 2 is a section of the same, showing the drop-spring and catch.

Figure 3 is a perspective view of the apron of the "Adams press," so called, from which is fed the sheet to be printed; the gauge, as applied to the apron in two places, when ready for use; also part of the fastenings of the gauge to the apron, and the two points in the apron, which hold the sheets of paper in place.

The letter A represents the gauge.

a, the drop or guide.

b, the spring.

c, the finger-catch.

d, a slot in the gauge, through which pass the fastenings.

e, slot in gauge, for the drop to operate in.

B, (fig. 3,) the apron.

f, the flat heads of the thumb-screws, securing the gauges to the apron.

g, metallic points or pins in the apron, upon which sheets of paper are secured, and held in exact position while either side of the paper is being printed.

Nature and Objects of the Invention.

The sheet-gauge, for printing-presSES, is a strip of sheet-metal, about twelve inches long and three inches wide, having a shoulder or rest near one end, against which the sheets rest when they are to be pointed, and spread out upon the apron preparatory to the impression of the type. Two are used, and fastened to the apron, at about equal distances from a line connecting the points in the apron. This gauge is used with what is known as the Adams printing-press.

In printing, the gauges are first fastened to the apron by some device, generally a thumb-screw, having a flat head, the screw passing through a slot in the gauge, its head resting upon the adjacent edges of the slotted parts, and the nut fastening it underneath the apron. The sheet is then laid on the apron to these gauges, or one end of the paper rests against the shoulders, and the sheet is then pressed upon the

points, which hold it fast, when the sheet is ready to be fed for the first side.

After printing one side, the sheet is turned over and again pointed; and in order that both sides of the sheet may be evenly printed, the points must, of course, enter the perforations already made.

The gauges, as they are now constructed and used, must be moved out of place, that is, unscrewed and slipped off the apron, so that the sheet may go on the points without obstruction, and lie perfectly free and smoothly upon the apron, and the gauges must be set to the edges of the sheet and pointed again. This operation, of course, consumes time, and much care must be taken to have the shoulders of the gauges evenly set, or in their former places.

The improvement will be clearly seen, thus:

When the gauges are fastened to the apron, in their proper places, and one side of the sheet is printed, instead of unscrewing and moving them, the shoulders are pushed down, leaving the apron free for the sheet to be turned and pointed, and then, by a move of the hand, they are reset in their proper places.

General Description.

The improvement will be readily understood by examining the drawings.

At e e, fig. 1, are traverse slots in the gauge, through which the drops a a pass, constituting the shoulders. When the sheet is to be turned, and readjusted upon the apron, the drop is pushed down, with the hand, below the surface of the gauge, and everything is free for the next form, by pushing up again the drop, and the pressman is sure his margin is the same as on the previous form.

The drop is in the form of a hinge, fastened to the under side of the gauge, at the bend seen in fig. 2.

There is also a spring, b, resting upon the hinge, keeping the drop in place, whether up or down.

c is a catch, simply for the finger, in pushing up or down.

What I claim as my invention, and desire to secure by Letters Patent, as applied to the sheet-gauge for printing-presSES, is—

The arrangement of the drop a, the spring b, and the catch c, with the gauge A, all being combined and operating substantially in the manner and for the purposes described.
